UNITED STATES PATENT OFFICE.

JACOB E. NEAHR, OF HARTSDALE, NEW YORK.

MATCH SAFE.

Application filed May 7, 1921. Serial No. 467,726.

To all whom it may concern:

Be it known that I, JACOB E. NEAHR, a citizen of the United States, residing in Hartsdale, in the county of Westchester and State of New York, have invented certain new and useful Improvements in Match Safes, of which the following is a specification.

This invention relates to match-safes provided with match-striking surfaces, especially surfaces that are coated with destructible ignition material.

One of the objects of the invention is to provide an inexpensive match-safe having a prepared ignition surface designed for giving long service and to be readily renewable, and to accomplish this by simple means easily understood and manipulated.

In carrying out my invention in one form, a tube of cardboard, wood or other material is exteriorly coated with ignition material to form a match-striking surface. This tube also forms a match receptacle, and is inserted vertically into a socket or frame. Said socket stands upon a suitable base, which preferably is also formed to serve as an ash tray, the socket or frame being in the form of a hollow pedestal rising from the ash tray and containing the tubular match receptacle. Portions of the coated exterior of the match receptacle are exposed through apertures in the socket or frame, so that a match may be ignited by striking it upon a portion of the tube, which is exposed through an aperture.

The tubular match receptacle may fit somewhat loosely within the socket or holder, so that it may be rotatively adjusted from time to time, to expose fresh striking surfaces through the aperture or apertures for use.

The match receptacle is preferably provided with a floor about midway of its length, upon which the matches may rest. Preferably a plug about half as long as the receptacle is inserted therein, the end of the plug serving as a floor. The receptacle may be withdrawn and inserted bottom end up, thereby enabling its coated surface to render further service for ignition, and the plug may be thrust into the other end of the tube, so that the matches may stand upon the other end of the plug.

Other features and advantages will hereinafter appear.

In the accompanying drawings, Figure 1 is a perspective view of one form of the invention.

Figure 2 is a central sectional elevation of the structure seen at Figure 1.

Figure 3 illustrates the plug occupying the lower end of the tube, to form a support for the matches, this being the preferred form of the invention.

Figure 4 shows a preferred design of socket or holder for the tubular match receptacle.

Figure 5 is a view of the match receptacle, showing the adjustable plug therein.

The matches 10 are placed in a stiff vertical tube 11 of paper or other suitable material, having a coating 12 of ignition material. In practice, a multiple length tube may be coated and cut up into sections, to serve as match receptacles. The receptacle 75 11 is dropped into a socket 13 formed centrally in a pedestal 14, which stands upon a base 15, the latter preferably formed with an ash-tray portion 16. This base may be made of wood or other material, and the pedestal 14 may be made of different material and secured in a seat 17 formed in the base. The pedestal or part 13 preferably has a bore extending entirely through the pedestal from top to bottom, to form the 80 socket, so that the match receptacle or tube 11 may rest directly upon the base 15. The pedestal has a top annular flange 18, and between said flange and the base apertures 19 are formed, through which ample surfaces of the ignition material 12 are exposed for use in striking matches.

In using the device, the flange or brim 18 may afford a support for the hand, whereby the device is held down firmly upon the 95 table as the match is being struck. Preferably the apertures 19 extend from top to bottom of the pedestal or holder 14, so as to give a long sweep for the match being struck, and these apertures, which are preferably narrow and long, may have an inclined or helical arrangement, as seen at 20, Figure 4, so that the match may be drawn a little to the left as it descends, this being a more convenient direction in which to move the hand that holds the match.

Certain portions of the ignition surface 12 are covered by solid upright bars 21 of the socket or pedestal 14, and only the portions of the ignition material which are ex- 110

posed between the bars are used; but after these portions are worn out, the match receptacle may be rotatively adjusted, so as to expose for use fresh portions of the ignition material or surface 12. Preferably the width of the bars 21 is about equal to the width of the apertures 19, so that a single adjustment of the tube may suffice.

A user of the device may provide himself with a supply of receptacles and at any time withdraw a worn-out receptacle and insert a fresh one, the receptacles being insertable either end first. Each aperture may be widened at its upper end, as at 22, for convenience in inserting the tip of the match. It will be seen that after a receptacle or tube has been partially used, it may be withdrawn and inserted the other end up, thus increasing its life.

In order to permit a match stroke of sufficient length, the receptacle has to be made so long that a floor 22^a is provided therein, upon which the matches may rest. This floor may be about midway of the tube. In place of a disk forming a double floor 22^a, at Figure 2, I preferably employ a cylindrical plug 23 of wood or other substance, which may rest upon the base 15 and extend about half way up the tube, thereby forming a match rest. This plug may be pushed to the other end of the tube when it is desired to invert the same, so that the other end of the plug will serve as the match floor.

Variations may be resorted to within the scope of the invention, and portions of the improvements may be used without others.

Having thus described my invention, I claim:

1. The combination of a pedestal having a suitable support and having apertures, and a match-container inserted in said support and comparatively narrow and high to

support laterally matches upstanding therein, and having a match-striking surface exposed through the apertures, said match-container being rotatively adjustable to expose different portions thereof through the apertures, and comprising a permanent floor to support matches upstanding thereon within the apertured portion of said support, said apertures on all sides of the support and extending downwardly in a helical direction.

2. The combination of a base comprising an ash tray portion, a pedestal rising from said base and having a vertical cylindrical socket, and a tube inserted in said socket and having a permanent floor to form a relatively narrow and high receptacle and lateral support for matches standing on end within said socket, said tube exteriorly coated with ignition material and rotatively adjustable, and said socket having openings through which the coating is exposed.

3. The combination of a base comprising an ash tray portion, a pedestal rising from said base and having a vertical socket, and a tube inserted in said socket to form a rotatably adjustable receptacle for matches, said tube exteriorly coated on all sides with ignition material, said pedestal having a top annular flange or brim, and provided with apertures below said brim through which the ignition material is exposed for use, said openings narrow and long, and extending up and down the pedestal, and inclined or having a helical arrangement, and said receptacle relatively narrow and high to afford a lateral support for matches standing therein.

JACOB E. NEAHR.
